United States Patent Office

Des. 184,329
Patented Feb. 3, 1959

184,329

BILLIARD TABLE OR THE LIKE

Robert I. Anderson, Muskegon, Mich., Richard G. Reine-
man, Covina, Calif., and George E. Schaefer, Muske-
gon, Mich., assignors to The Brunswick-Balke-Collen-
der Company, Chicago, Ill., a corporation of Delaware

Application March 26, 1958, Serial No. 50,189

Term of patent 14 years

(Cl. D34—3)

Fig. 1 is a top plan view of the billiard table or the like showing our new design;

Fig. 2 is a front elevational view thereof;

Fig. 3 is an end elevational view, taken from the right end of the table as illustrated in Figs. 1 and 2; and

Fig. 4 is an end elevational view, taken from the left end of the table as viewed in Figs. 1 and 2.

The dominant features of our design are shown in full lines.

We claim:

The ornamental design for a billiard table or the like, as shown and described.
